CLAIM

The ornamental design for a tire tread, as shown and
described.

DESCRIPTION

FIG. 1 is a perspective view of a tire tread showing my new
design;

FIG. 2 is a front view thereof;

FIG. 3 is a top view thereof;

FIG. 4 is a right side view thereof;

FIG. 5 is a left side view thereof;

FIG. 6 is a fragmentary enlarged view showing the details of
tire tread thereof;

FIG. 7 is a section view taken along line 7-7 in FIG. 6;

FIG. 8 is a section view taken along line 8-8 in FIG. 6; and,
FIG. 9 is a section view taken along line 9-9 in FIG. 6.

Broken lines in the drawings are intended to show portions
of the tire that are not being claimed, and thus form no part
of the claimed invention.
